ETCHING MACHINES

John F. Lear, Easton, Pa., assignor to Industrial Gravure Co., Easton, Pa., a corporation of Pennsylvania
Filed Sept. 14, 1964, Ser. No. 396,116
17 Claims. (Cl. 134—147)

The present invention relates to an etching machine and, more particularly, to machines of this type for etching metallic printing plates or segments having an arcuate or cylindrical contour.

Accordingly, the principal object of this invention is to provide an etching machine that will impinge or propel the etchant against the curved surface in such a manner as to more accurately contact all sides of the image area thus producing a more uniformly etched image.

A further object of the invention is to provide such a cooperative organization of elements that will insure proper etching of the curved plate or cylinder and furnish a much greater perfection in colors.

A still further object of the invention is to provide a means having such versatility of adjustment that it will provide more accurate peripheral speed for all sizes of cylinders or their counterpart—the arcuate segment or curved plate.

Another object of the invention is to provide an adjustable speed control drive means by means of which the peripheral speed of the curved plate may be more accurately controlled, thus insuring uniform application of the mordant to the curved surface thereof.

Still another object of the invention is to provide a unique drive means for the work supporting means.

A still further object of the invention is to provide a new etching machine having a high efficiency for more accurate production of etched plates and one which is economical to manufacture and is of a relatively simplified construction.

The details of the invention, as well as additional objects and advantages, will be clearly understood with reference to a preferred embodiment illustrated in the accompanying drawings employing similar reference numerals to identify the same elements in each of the several views, and in which:

FIG. 1 is a side elevational view partially in section of the improved etching machine;

FIG. 2 is a front elevational view partially in section of the new etching machine;

FIG. 3 is an enlarged perspective view of the front of the machine showing in further detail the preferred embodiment of the invention disclosed herein;

FIG. 4 is an enlarged transverse sectional view through the etching chamber taken on line 4—4 of FIG. 1;

FIG. 5 is an enlarged perspective and more detailed view looking into the tank showing partially in section the flinger disc which induces return of the etchant to the chamber of the machine;

FIG. 6 is another enlarged perspective view looking out of the tank with the paddle shaft and flinger disc omitted for clarity and also clearly showing the upper and lower halves of the tank;

FIG. 7 is another enlarged perspective view of an alternative form of the invention showing in detail the drive means for the work supporting means;

FIG. 8 is an enlarged front elevational view partially in section taken on line 8—8 of FIG. 9;

FIG. 9 is a sectional view on line 9—9 of FIG. 8; and

FIG. 10 is a fragmentary sectional view on line 10—10 of FIG. 9.

Turning now to a description of FIG. 1, which, together with FIGS. 2, 3, 5 and 6, show the preferred embodiment of the invention there is shown an elevated

2

platform 10 the top portion 11 of which forms a base for the etchant tank or receptacle 12.

From an examination at this time of the various views of the etching machine it will be observed that it comprises a receptacle which is substantially rectangular and includes front, rear, side and top walls, latter of which is provided with hinge means extending along the perimeter or top edges of the opposed side walls. As has been shown fragmentarily in FIG. 2, the hinged top wall 10 separates along a line extending parallel with but above the axis of the work support means which will be described in greater detail later.

With reference to the tank 12, and the view in FIG. 1, it will be noted that the receptacle is constructed of two complementally formed halves separable along a horizontal line with the upper portion being designated 13 and the lower portion being identified as 14, with the latter forming a chamber for the etchant, or if desired adaptable to receiving a separate or removable tray means, not shown. As is best shown in the detailed views of the butt joint for the tank (FIGS. 5 and 6) the perimeter 15 of the lower half of the tank at its front and rear walls is dished out or undercut to a predetermined extent to provide diametrically opposed slots for a purpose that will become apparent. The top half of the tank indicated at 13 has secured thereto, by means of welding, at its lower extremity suitable elongated strap elements 17 and 18 which straddle the rim of the lower portion of the tank and thereby function as guide means when the upper portion of the tank is being lowered into position in abutted arrangement with the lower portion. As the description progresses, it will become apparent that by constructing the etching tank in this manner access may be readily had thereto for removing and replacing the paddles as well as thorough cleaning of the inside of the receptacle.

General description of the drive mechanism

At this time by referring to FIG. 2 it will be seen that an upstanding frame work 19—19 including bases 20—20 are adapted to be positioned adjacent to one side of the machine and are, thus, arranged to support, by means of a vertically extending web 21 the gear reducing means 22 from the opposite ends of which project stub shafts 23 and 24 to which are revolvably secured drive sprocket means 25 and 26. Referring once again to FIG. 2 (as well as FIG. 1) it will be seen that the upper portion of the framework 19—19 is provided with upstanding bearing means 27 and 28 adapted to revolvably support therebetween an elongated horizontally disposed shaft 29 adjacent to the opposite ends of which are keyed sprocket means 30 and 31. Another drive sprocket 32, the circumferential area of which is predetermined to provide the desired drive speed for the revolute work supporting means is keyed to shaft 29 at a position directly above sprocket 25 so as to be coplanar therewith and, thus be arranged to receive a drive chain 33 which is entrained therebetween.

Positioned above the base 11 of the framework at the opposite ends thereof are brackets or shelves 34 and 35 which support sprocket drive means 36 and 37 that in turn revolvably carry the opposed end portions of shaft 38 and to substantially the medial area of which is keyed a sprocket 39 of adequate circumferential area to function as a power input into the gear reducing mechanism 22 by means of an endless drive chain shown at 40. The driving motor 41 may be positioned at any preferred point in the area of the input shaft 38 and, thus, is only schematically shown in FIG. 2.

The previously described sprocket means 30 and 31 drive into gear means 42 and 43 carried adjacent to each end of the shaft means 44 which forms the axis of the

work support means 45 with each end of the shaft means being arranged to project through the opposed perpendicularly slotted areas 46 and 47 in the front (and rear) wall of the tank 12. The reel 45 which forms the work supporting means in this disclosure is of a well-known type such as shown in the earlier prior art patents. The gear reducer 22 is of a type now commercially available.

Referring once again to FIG. 1 and then to FIG. 2, it will be noted that a sprocket means 39 driven by the input shaft 38 is revolvably associated with the paddles 48 and 49 by drive chain means.

Each of the paddles 48 and 49 include axially extending shafts 50 and 51, respectively, which project through the slotted area 15 at the front of the tank wall referred to hereinbefore. As is probably best shown in FIG. 1, the drive chain means 52 is entrained about sprocket means 37 carried by the input shaft from whence it travels upwardly to and about idler means 53, thereafter substantially perpendicularly thereto to engage a lower sprocket means 54 carried by the shaft 50 up an inclined plane toward the sprocket gear means 55, carried at the shaft end of the adjacent paddle, then downwardly about another idler means 56 and thence rearwardly back toward the input shaft 38. It will be apparent from an examination of FIG. 4, that the manner in which the chain is entrained about the sprocket means carried by the paddles as well as the idlers, that the paddles will be driven in opposition to each other, thus resulting in a convergent flow of the etchant from the bath toward the work supporting means.

Referring now to FIGS. 2 and 3, it will be seen that adjacent to the front of the etching machine and in spaced relation thereto and supported on the base 11 are a series of vertically disposed, transversely extending plates 57, 58, and 59, with the medially disposed of said series of plates, i.e., 58, extending above the plane of the plates disposed on the opposite sides thereof for a purpose that will become apparent as the description progresses.

Since the vertically disposed plates 57 and 59 are substantially identical only one will be described. At the lower extremity of plate 57 there is provided a right angular integral outwardly extending foot portion 60. The foot portion 60 may be secured to the base 11 by bolting, welding or any other suitable means.

In spaced arrangement above the foot 60 there is shown an offstanding angular upturned L-shaped element 61 which acts as a support for the bottom edge of the slide 62. In spaced relation above element 61 is a complementary downwardly extending L-shaped guide means 63 which is in sliding engagement with the top edge of the slide 62, thus, together the pair of elements form a guide means for slide 62. At this time attention is directed to the right-hand portion of FIG. 1, where it will be observed that the paddle shaft 50 is arranged to project through a perforation in slide 62 (FIG. 3) and thence into a bearing means 64 carried on the outer surface of the slide 62.

As viewed best in the fragmentary perspective view of FIG. 5, there is disclosed a portion of the front wall of the tank through which the shaft 50 of paddle 48 is arranged to project, as described hereinbefore. In this view the abutted arrangement of the top portion 13, as well as the bottom portion 14 of the tank together with the strap elements 17 and 18 are likewise shown. As shown in FIG. 5 and the exterior front portion of the tank 65 there are spot or tack welded at their flange portions 65 and 66, above and beneath the separation area of the complementary formed plates 67 and 68, the overlapping edges of each of which are deformed or undercut at 69 and 70, thus together forming a slot which is complementary to the slot formed in the tank, best shown in FIG. 6 and within which the rotatable shaft 50 may reciprocate in a horizontal path.

A flinger disc or baffle 71 comprising a centrally aper-

tured annulus is affixed to and revolvably supported on the shaft 50 and will deflect any liquid which is emitted from the slotted area in the walls of the etching receptacle back toward the weep hole where it will return to the tank.

It is to be understood, of course, that all of these elements are duplicated in the other half of the tank, in that the paddle 49 also includes a shaft 51 and flinger disc 72 with the end of the shaft 51 being supported in a bearing means 73 which is secured to slide means 74.

The medially disposed plate 58 is also provided with opposed channel guide means 75 and 76 in the upper area thereof adapted to slidably support plate 58. The outwardly extending extremity of the shaft axis 44 of the reel or work support member extends through a perforation in the plate 58 and is supported in a bearing means 77.

Considering first the vertical adjustability of the work support means through the axially extending shaft 44 thereof, this is accomplished by means of the perpendicularly disposed shaft 78 which has its upper portion externally threaded as at 79 and thus adapted to be received in an internally threaded bearing means 80 suitably secured to the outer surface of slide 81, as shown.

At the lowermost extremity of shaft 78 there is affixed by means of a key a bevel gear 83 which in turn is driven through a complementary bevel gear 83 secured to the end of the horizontally disposed shaft means 84. The exterior surface of plate 58 is provided with bearing means 85 and 86 the bases of each of which are provided with suitable spacing means 87 and 88, respectively, to permit exact perpendicular disposition of the shaft 78.

Relative to the arrangement for accomplishing the simultaneous advancement toward each other as well as the receding movement from each other, the slides 62 and 74, respectively, are provided on their exterior surfaces adjacent to their opposed edges with internally oppositely threaded nut means 89 and 90, which are adapted to receive a shaft means 91 that is supported in spaced bearings 92 and 93. The opposed end portions of shaft 91 are externally threaded in opposite directions to correspond to the directional threading of the nut means 89 and 90, thus permitting the slides to simultaneously reciprocate linearly in a horizontal plane to-and-fro. A sprocket means 94 is keyed to shaft 91 and is arranged to be driven therefrom by a chain means 95 endlessly entrained about revolvably supported sprocket 96 which is in turn keyed to and revolvably carried by the shaft 99 which is supported at its opposed ends in bearing means 97 and 98. The bearing means 97 and 98 are supported in a position offstanding from the exterior surface of the slides 62 and 74 through spacer means which may constitute metal blocks bolted or otherwise secured to the reciprocable slides.

As best shown in FIG. 3 the ends of shafts 84 and 91 may be provided with sprocket members 101 and 102 for a purpose now to be described.

Each of the shafts 84 and 91 are provided at their uppermost extremities adjacent to the upstanding corner of the machine with pin means 103 and 104 by which rotation of the shafts 84 and 91 may be achieved by means of manually rotation of a crank, not shown. As schematically shown in FIG. 3, the sprocket means 105 and 106 carried adjacent to the outer extremities of the shafts 84 and 91 are adapted to be driven together or simultaneously by means of a crank applied to either shaft through the medium of a chain entrained thereabout. Thus, when the chain 107 is applied to the sprocket means 105 and 106 in the manner schematically shown, and a crank is applied to the end portion of either of the shafts 84 or 91, the slides 62 and 74 can be reciprocated gradiently to-and-fro, thus causing the slides to advance forward or recede from each other depending upon the direction of rotation of the crank applied to the shafts and simultaneous therewith the slide 81, which is adapted to revolvably support the offstanding axis of the work support means

45, is moved perpendicularly relative to the supporting bracket 58. Thus, it will be readily apparent that when the sprocket means 105 and 106 are driven in unison by the chain 107 there is a resultant gradient raising and lowering of the work support means relative to the gradient simultaneous to-and-fro movement of the horizontally arranged slides 62 and 74. Of course, it is apparent from the foregoing that upon removing the chain 107 from its entrainment about sprocket members 76 and 77 each of these shafts may be driven independently of the other to, thus raise perpendicularly the slide 81 which supports the work support means 45 as well as to reciprocate the slides 62 and 74 back and forth relatively to each other.

The foregoing disclosure which generally relates to the gradient reciprocal movement of the paddle means, to-and-fro relative to the front and rear of the tank while at the same time the work support means is coordinated therewith, is not intended to be restrictive of the invention disclosed but merely one manner in which it may be utilized. Further, by way of illustration, attention is directed at this time to FIG. 2 where it will be noted that the chain 107, discussed hereinbefore, is not illustrated and also the fact that the work support means is shown at the top of the slotted area in which it is confined for vertical movement. It is conceivable particularly in view of the modifiability of the components of this improved etching machine that an operator could avail himself of an oversize work support means which during experimentation would require that the gradient movement of the slides and the work support means relative to each other be varied more than permissible when the chain 107 is utilized. In addition, the longitudinal area of the slotted openings in which the elements are adapted to reciprocate is only considered to be representative for it is contemplated that by elongation of each of the means defining the slotted openings the slides as well as the work support means can be brought into closer proximity to one another.

This etching machine, it will be thus observed, is far more versatile than any others that have been known heretofore. By experimentation, which is available in the unusual design and construction of this etching machine depending upon the ability and knowhow of the operator, much more refined etchings showing considerably reduced undercutting may be achieved.

Turning now to the alternative form of the invention shown in FIGS. 7 through 10, and referring particularly at this time to FIG. 7, there is shown in an enlarged perspective fragmentary view a portion of the front wall of the tank at 200 with the work support means being clearly shown in the cut away view therebehind. The upstanding bracket means 201 together with the guide means 202-202 formed therewith are only generally and fragmentarily shown since this portion of the etching machine is substantially identical to the preferred embodiment thereof described above.

The reciprocable slide means 203 and 204 are only fragmentarily illustrated with the shafts 205 and 206 which carry the paddles (not shown) extending through perforations in said slides and rotatably supported in bearing means 207 and 208.

In this alternative embodiment of the invention the shaft 209 extends from adjacent to the edge of the bracket, (not shown in FIG. 7 but see FIG. 3), horizontally past the slides 204 and 203 with the oppositely threaded areas thereof indicated at 210 and 211 being intercepted by nuts means 212 and 213 each of which are secured to the reciprocable slide means 203 and 204, respectively.

As previously described in connection with the preferred embodiment of the invention the bracketed supporting means for the gradient reciprocation of the several slide means, including the intermediate bracket means for slidably supporting the work support means in a perpendicular direction to-and-fro, this embodiment also includes a similar upstanding intermediate bracket means at 201,

which is arranged in spaced relation to the front of the tank. (FIG. 9). However, in this embodiment of the invention the bracket 201 is provided with a pair of vertically arranged slots shown at 214 and 215 for a purpose that will become apparent later. This form of the invention also includes a vertically disposed shaft 216 the upper portion of which is threaded at 217 and adapted to engage with an enlarged horizontally disposed nut 218 with the lower end of said shaft being provided with a bevel gear 219 which is in driven engagement with a driving bevel gear 220 carried at the inner end of the horizontally arranged shaft 221 all of which will be understood from the description of the preferred embodiment.

The rear extremity of nut 218 is secured to an upstanding block 219 by bolting or welding, said block being arranged in face-to-face contact with the slide 228 and adapted to support an offstanding shelf member 222 which has complemental portions that extend to the front and rear of the slide and include vertically extending support or carrier elements 223 and 226 which, provided with a pair of spaced perforations are adapted to receive suitable bearing means.

A vertically disposed slide 228 which includes a pair of horizontally arranged apertures provided with bushings 229 and 230 is confined within the guide rails 202-202 provided at the oppositely disposed inturned edges of the bracket 201 with said slide being adapted to receive a pair of horizontal spacedly arranged shafts 231 and 232 in said bushings. The outwardly extending end of shaft 231 is provided with a drivable gear or sprocket 233, with inwardly extending ends of shafts 231 and 232, which terminate substantially directly within the front wall of the tank being provided with pinions 234 and 235 (FIG. 10). However, whereas the outwardly extending portion of shaft 231 is provided with the sprocket 233 the shaft 232 terminates adjacent to the bearing means 227 as best shown in FIG. 7.

It is now believed that the reader will understand that by imparting a driving rotation to the gear 233 the pinions 234 and 235 which are disposed within the tank and are adapted to support therebetween the pinion 236, which is supported adjacent to the extremity of the axially disposed shaft 44, the work support means will in turn also be driven.

From the foregoing it will be apparent that in this form of the invention the work support means is readily removable from the tank for adjustment of the individual carrier members as well as to secure the curved plates or cylindrical bodies thereto. The pinion 236 carried by the reel may be lifted out of supporting engagement with gears 234 and 235 merely by securing the lower end of hook 238 beneath the shaft 44 between the vertical end wall of the reel and the rear face of the gear 236. To assure proper assembly of the reel carried pinion 236 with the supporting pinions 234 and 235 the inside of the front and rear walls of the tank are provided with guide rails 240 (only one shown) (FIG. 8) which are arranged to receive the nose portion 241 at the end of the shaft 44, said nose portion extending beyond pinion 236, as best shown in FIG. 9.

As viewed best in FIG. 9, the carrier 226 which supports the innermost of the bearing means lies flush against a plate 245 which is provided with a horizontally spaced pair of apertures said plate being adapted to be supported by and moved perpendicularly relative to the front wall 65 of the tank with the pinion carrying shafts 231 and 232.

The inwardly extending surface or wall of the plate 245 which offstands from the exterior surface of the front wall of the tank is provided with horizontally spaced splash collars 246-246 which surround each of the shafts 70 231 and 232 (only one shaft shown) the outwardly extending portion of each of the splash collars being concentric with and telescoped by complementarily arranged splash collars 247-247 (one shown) one each of which are secured to the rear surface of the pinions 234 and 235. The splash collars may be secured to the plate 245 as

well as to the pinions 235 and 235 either by braising, welding or any other suitable means. Thus, it will be apparent that with the inclusion of the plate 245 and the telescoping splash collars the etching material which passes through the slotted area in the front wall of the tank, either in the form of mist or droplets, will not come into contact with the innermost bearing means.

Also, as best shown in FIG. 9, a cover element or shroud 250 provided with a pair of vertically extending slotted areas complementary to the circumferential area of pinion shafts 231 and 232 will confine the etchant mist which passes through the slotted area in the tank wall and eventuates into a liquid, to the bleed hole, thus leading the liquid back to the tank and the etchant chamber therein.

Whereas the mechanism described heretofore and which is particularly adapted to perpendicular movement of the axially extending work support means as well as those means which gradiently reciprocate the slides in a horizontal direction to-and-fro is only shown positioned adjacent to the front wall of the etching machine it is to be understood that these elements are also duplicated at the rear wall of the machine and arranged to be driven by the chains schematically shown at 251 and 252 about which are entrained sprockets 253 and 254 the latter being keyed to and manually driven by shafts 91 and 84, respectively.

Although the description of this invention as well as the drawings which accompany it disclose, paddle means as being the medium by which the etchant is lifted from the bath contained in the tank and projected against the work it is considered to be within the scope of this invention to correlate spray means on the opposite sides of the tank, as distinguished from the paddle means shown, and likewise control their reciprocal gradient movement to-and-fro relative to the work support means, thus in this manner also obtaining a controlled application of the etchant to the work and reducing undercutting thereof.

Although two embodiments of the invention have been depicted and described, it will be apparent that these embodiments are illustrative in nature and that a number of other modifications in the apparatus and variations in its end use may be effected without departing from the spirit or scope of the invention as defined in the appended claims.

What is claimed is:

1. In an improved etching machine providing for perpendicular adjustment of a horizontally disposed work supporting means relative to coplanar reciprocably disposed etchant applying means the combination comprising, a substantially enclosed tank provided with front, rear, side and top walls having a chamber in the bottom thereof adapted to receive a bath of etchant fluid, coplanar horizontally disposed reciprocable means for projecting fluid in a convergent direction toward the surface of the work supporting means and means providing for reciprocation of the fluid projecting means toward and away from the axis of the work supporting means as said last named means is raised and lowered in a vertical plane relative thereto.

2. In an improved etching machine providing for perpendicular adjustment of a work supporting means relative to the bath of etchant the combination comprising a substantially enclosed tank provided with front, rear, side and top walls having a chamber in the bottom thereof adapted to receive a bath of etchant fluid, coplanar horizontally disposed reciprocable driven paddle means positioned in contact with the fluid in said chamber for impelling liquid from the bath in a convergent direction toward the work supporting means and means providing for actuation of the liquid impelling means toward and away from the axis of the work supporting means as said last named means is raised and lowered in a vertical plane relative thereto.

3. In an improved etching machine as claimed in claim

1, wherein the driven means for the horizontally disposed reciprocable means comprises a power means.

4. In an improved etching machine as claimed in claim 1, wherein the driven means providing for perpendicular adjustment of the work supporting means is a power means.

5. In an improved etching machine as claimed in claim 1, wherein a single power means actuates the work supporting means and said liquid projection means.

6. In an improved etching machine as claimed in claim 1, wherein the tank is constructed of complementary, separable top and bottom portions.

7. In an improved etching machine as claimed in claim 2, wherein the front and rear walls of the etchant receptacle are provided with means defining elongated horizontally slotted openings therein, diametrically opposed shaft portions provided at each extremity of the paddle means arranged to be received in said means in said front and rear walls, slide means movably positioned adjacent to said means in the front and rear walls and bearing means carried by said slide means adapted to support said shaft means.

8. In an improved etching machine as claimed in claim 7, wherein the slide means are actuated by power means.

9. In an improved etching machine as claimed in claim 1, wherein the work supporting means is provided with an axially extending revoluble shaft means having diametrically offstanding portions, means defining complementary slotted areas in the opposed sidewalls of said tank adapted to permit extension of said shaft means therethrough and vertically reciprocable slide means supported in spaced relation to the sides of said tank wall adjacent to said slotted area and arranged to support said shaft means.

10. In an improved etching machine as claimed in claim 4, wherein means are provided for advancing and retracting the slide means relative to each other.

11. In an improved etching machine as claimed in claim 7, wherein the opposed shaft portions which extend through the front and rear walls of the tank are provided with flinger means, and complementary cover means carried by said tank walls shrouding said flinger means.

12. In an improved etching machine as claimed in claim 1, wherein each of the top side walls of the tank comprise hinged lid portions thereby permitting access to the interior of the tank.

13. In an improved etching machine as claimed in claim 1, wherein the work supporting means includes an axially extending shaft means arranged to project through the front and rear walls of the tank, bearing means adapted to revolvably support said shaft means and drive means carried by at least one end of said shaft means.

14. In an improved etching machine as claimed in claim 1, wherein the work supporting means includes an axially extending shaft, pinion means carried adjacent to at least one end of said shaft, plural drive means arranged to extend through the wall of said tank, pinion means carried by the inwardly extending ends of said drive means with the pinion of said shaft means being supported by and driven through said pinion means.

15. In an improved etching machine as claimed in claim 14, wherein the interior of the front and rear walls of said tank include offstanding guide means, stub shaft means extending beyond the pinion carried by said work supporting means and means for guiding said work supporting means relative to said drive means to position the same on the drive means.

16. In an improved etching machine as claimed in claim 7, wherein the slide means are provided with nut means, cooperative oppositely threaded means associated with said nut means, said threaded means being arranged to reciprocate said slide means.

17. In an improved etching machine providing for perpendicular adjustment of a horizontally disposed work

supporting means relative to coplanar reciprocably disposed etchant applying means the combination comprising, a substantially enclosed tank provided with front, rear, side and top walls, coplanar horizontally disposed reciprocal means for projecting etchant fluid in a generally convergent direction toward the surface of the work

supporting means and means for controlling the reciprocation of said horizontally disposed fluid projecting means relative to the travel of said work holding means.
